UNITED STATES PATENT OFFICE.

NICOLAUS AUGUST OTTO, OF COLOGNE, ASSIGNOR TO THE GAS-MOTOREN-FABRIK-DEUTZ, OF DEUTZ-ON-THE-RHINE, GERMANY.

APPARATUS FOR REGULATING THE SPEED OF GAS OR OIL MOTOR ENGINES.

SPECIFICATION forming part of Letters Patent No. 425,692, dated April 15, 1890.

Application filed January 25, 1890. Serial No. 338,115. (No model.) Patented in England December 30, 1889, No. 20,892, and in Belgium January 17, 1890, No. 89,210.

To all whom it may concern:

Be it known that I, NICOLAUS AUGUST OTTO, a citizen of Prussia, residing at Cologne, in the German Empire, have invented 5 new and useful Improved Apparatus for Regulating the Speed of Gas or Oil Motor Engines, (for which I have obtained Letters Patent in Belgium, dated January 17, 1890, No. 89,210, and in Great Britain, by an application 10 for patent, which patent, when granted, will bear date December 30, 1889, No. 20,892,) of which the following is a specification.

This invention relates to a mode commonly adopted for regulating the speed of gas or oil 15 motor engines, wherein the gas or oil vapor supply to the engine-cylinder is entirely cut off when the engine runs above the normal speed. In apparatus frequently used for this purpose in motor-engines of the well-known "Otto" type this is effected by mounting upon a counter-shaft a sliding sleeve having a cam, which, in the normal position of the sleeve, acts upon the gas-valve lever, so as to open the valve and admit gas to the 20 cylinder, but which is moved by the governor when the engine runs too fast, so that the cam misses the gas-valve lever, causing the gas-valve to remain closed. With this apparatus it sometimes happens that the sleeve is 25 brought into such an intermediate position by the governor that the roller of the gas-valve lever is just caught by the extreme edge of the cam, which consequently opens the valve; but the roller, in slipping off the edge again before the cam has completed its 30 action, causes the valve to close prematurely, resulting in an imperfect cylinder charge and a consequent miss-fire.

The present invention has for its object to 35 remedy this defect by preventing the possibility of the sleeve and cam assuming any such intermediate position and by rendering the governor more sensitive in reducing the resistance which it has to overcome. For 40 this purpose the governor-lever is not connected directly to the sliding sleeve, this being acted upon at every revolution of the counter-shaft by a cam on the latter, which, during the expelling-stroke of the engine-pis-

ton, depresses a lever (which may be the escape-valve lever) and causes this to move the cam-sleeve through the medium of an elbow-lever into the extreme position in which its cam escapes the gas-valve lever. This movement is effected against the action of a spring, 50 which consequently moves the sleeve back to its other extreme position as soon as it is released by the escape-valve lever, this being in its turn released by the before-mentioned cam on the counter-shaft as soon as the expelling-stroke is completed, so that the sleeve-cam is then brought into correct position for acting on the gas-valve lever again at the next admission-stroke. Thus the cam can only be brought into its two extreme positions. The governor acts upon a lever which is connected by a link to a rod pivoted at one end to the engine-frame and having its free end moved into different positions by the governor, according to the 55 speed of the engine, this movement of the rod being the only work the governor has to do, so that its action is rendered very sensitive. When the engine is running too fast, the governor brings the rod into a position in which 60 its end faces a notch on the escape-valve lever, so that when this has been actuated by its cam, as described, so as to bring the sleeve-cam into the position in which it misses the gas-valve lever, it is prevented from returning into its original position by the rod which 65 catches into the said notch. Thus it will be seen that the sleeve-cam will be held in the extreme position in which it misses the gas-valve lever until, by the reduction of speed 70 to the normal, the governor is made to move the end of the rod out of the path of the escape-valve lever, whereupon this can return 75 to its original position and allow the sleeve-cam also to move back into the position in which it acts on the gas-valve lever.

The accompanying drawings show the arrangement which it is preferred to employ in carrying out the above-described invention as applied to a gas-motor engine of the well-known Otto class, working with a cycle of 80 four strokes.

Figure 1 shows a front view of the appara-

tus; Fig. 2, a side view of the same. Figs. 3 and 4 are detail views of the cams for controlling the valve-gear and the cam-sleeve.

- c is the sliding sleeve on the counter-shaft 5 q, carrying the cam d, that actuates the gas-valve lever e. The sleeve is not actuated directly by the governor a, but is moved into its two extreme positions at each revolution of the counter-shaft by the following mechanism: 10 The lever f, which in this case is the lever actuating the escape-valve p of the engine, and is depressed for this purpose at each expelling-stroke of the piston by the cam g on the counter-shaft, carries a roller n, which acts on one 15 arm of a bell-crank lever m, whose other arm is connected to the sliding sleeve c, so that at each expelling-stroke of the piston the lever f, at the same time that it opens the escape-valve p, causes the sleeve c to be moved from 20 its extreme left-hand position, (indicated by dotted lines, Fig. 1,) in which the cam d acts upon the lever e, so as to open the gas-valve, into the extreme right-hand position, (shown in full lines,) in which the cam d is quite clear 25 of the lever e. This motion of the sleeve c is made in opposition to the pressure of a helical spring o, so that when the lever f is released by the cam g and is drawn back by its spring s the sleeve c, being no longer held by lever m 30 and roller n, will be rapidly pushed back into its left-hand position again, so that the cam d can act upon the gas-valve at the next charging-stroke.
- The governor a is connected to a bell-crank 35 lever b, which is connected by a link h and spring r to a rod k, pivoted at its upper end to the governor-bracket and having its lower end facing a notched projection l on the lever f.
- 40 When the engine is running at the normal speed, the governor-sleeve, being lowered, holds the lever b and rod k in such a position that the end of the latter is situated to the right hand of the notch l, as indicated by the 45 dotted line, Fig. 1, so that the lever f is free to be acted upon by the cam g and spring s at each revolution of the shaft q in the manner described. When, however, the engine runs too fast, the governor-sleeve in rising 50 causes the end of rod k to be brought in line with the notch l, so that when lever f is released by cam g, after being pressed down thereby, it can only move a slight distance upward in obedience to the spring s, when it 55 will be arrested by the rod k taking into the notch l, this being the position shown on the drawings; and it will be seen that when in this position the lever f still holds the sleeve c back, so that cam d cannot act upon the 60 gas-valve lever, thus preventing the admission of gas to the cylinder at the next charging-stroke. At each succeeding revolution of shaft q the cam g will move lever f to a slight extent away from the rod k; but on being 65 released by the cam the lever will be again stopped by rod k if the speed of the

engine is still such that the governor retains the rod in the same position. When, however, the speed is reduced to the normal again, then at the next time that lever f is 70 moved away from k by the cam the governor will move k to the right, so as to escape the notch l, and consequently lever f, in moving up its full stroke, will allow sleeve c to be moved back into the position in which cam 75 d again opens the gas-valve. The connection of lever b with rod k is by preference made somewhat elastic by means of the spring r and slotted rod h, in order to allow of a certain amount of variation in the governor's 80 position while the rod k is locked in the notch l; but this is not absolutely necessary, and the rod k might itself form part of a lever actuated directly by the governor, thus dispensing with the lever b.

85 Although the lever f in the arrangement above described serves both for opening the escape-valve p and for actuating the cam-sleeve c, yet it may in some cases be preferred to employ a separate lever actuated by a separate cam for this purpose. In this case the cam may be formed as indicated at g', Fig. 3—namely, so as to hold the cam-sleeve c out of gear with e during the compressing, working, and expelling strokes, and only give it liberty 90 to move into gear during the charging-stroke, when the action of cam d is required. By this means the governor will in all cases be perfectly free to move the rod k during the said three strokes, and this will only be held during the charging-stroke when the engine runs 95 too fast.

100 When the cam g, that works the escape-valve p, is employed for the above purpose, it requires, of course, to be formed as shown at Fig. 4, so as under normal working to limit the out-of-gear position of the sleeve c to the time during which the valve p requires to be open, and the governor would of course in that case only be free to move the rod k during the 105 expelling-stroke when the engine runs too fast.

110 The sleeve c might be extended in length and carry two or more cams for actuating an air-admission valve, &c., as well as the gas-valve.

115 Instead of actuating the cam-sleeve c by the above-described mechanism, it might be made stationary, and the lever m be made to move the gas-valve lever e laterally, so as to come alternately into or out of gear with the cam d in precisely the same manner as above described. The lever e may be made with a spring-joint or with spring action for this purpose. Lastly, the motion of the lever f can be imparted to the lever m otherwise than 120 through the roller n—such as by a ball-and-socket joint; also, instead of causing the governor to arrest the motion of the lever f when the engine runs too fast, it may be made to 125 actuate a device that will hold either the bell-crank lever or the sleeve c itself in the out-of-gear position.

Having thus described the nature of my invention and the best means I know for carrying the same into practical effect, I claim—

1. In apparatus for controlling the speed of gas or oil motor engines, the combination of a sleeve on the cam-shaft carrying the cam that actuates the gas-valve lever and receiving a to-and-fro motion at each revolution of the cam-shaft, so as at one time to gear with the gas-valve lever and at another time not to gear therewith, a lever acted upon by a second cam on the cam-shaft for imparting the said to-and-fro motion to the cam-sleeve, and a rod or equivalent device actuated by the governor, so that when the engine runs too fast the said rod is brought into a position in which it holds the lever and cam-sleeve in the position in which the cam cannot actuate the gas-valve lever, substantially as herein described.
2. In apparatus for controlling the speed of gas or oil motor engines, the combination of a sleeve capable of sliding on the cam-shaft and carrying the cam that actuates the gas-valve lever, a spring tending to keep the sleeve in the position with which its cam gears with the gas-valve lever, a bell-crank lever adapted to move the sleeve out of the said position in opposition to the spring's action, a second lever acted upon by a cam on the cam-shaft and gearing with the bell-crank lever for imparting the requisite motion thereto, and a rod or equivalent device actuated by the governor, so as to be brought thereby into a position in which it arrests the second lever in the position in which the sleeve-cam is out of gear with the gas-valve lever, substantially as described.
3. In apparatus for controlling the speed of gas or oil motor engines, a sliding cam on

a cam-shaft which is urged by a spring into the position in which it gears with the gas-valve lever and is moved in the contrary direction, so as to be out of gear with the said lever, by a lever acted upon by a second cam on the cam-shaft and operating the sliding cam through the medium of a bell-crank lever or equivalent device, substantially as described.

4. In apparatus for controlling the speed of gas or oil motor engines, a lever operated by a cam on a cam-shaft, such lever being adapted both to open the escape-valve of the engine-cylinder and at the same time to move the sliding cam that operates the gas-valve lever into the position in which it is out of gear with the latter, substantially as described.

5. In apparatus for controlling the speed of gas or oil motor engines, the combination of a lever actuated by a cam for moving a sliding cam out of gear with the gas-valve lever, a pivoted rod adapted to lock with the said lever, so as to keep it in the position in which the sliding cam is out of gear, and a lever actuated by the governor and connected to the said rod by an elastic connection, so that the governor is free to move with the bell-crank lever while the rod is locked in position, substantially as herein described.

In testimony whereof I have signed my name to this specification, in the presence of two subscribing witnesses, this 7th day of January, A. D. 1890.
